United States Patent Office.

AMOS NUDD, OF WAUPUN, WISCONSIN.

Letters Patent No. 65,936, dated June 18, 1867.

IMPROVEMENT IN MELODEONS, &c.

The Schedule referred to in these Letters Patent and making part of the same.

TO ALL WHOM IT MAY CONCERN:

Be it known that I, AMOS NUDD, of Waupun, in the county of Fond du Lac, and State of Wisconsin, have invented certain new and useful improvements in Sounding-Boards for Melodeons, &c.; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use the invention, I will proceed to describe it.

My invention consists in applying to melodeons and all similar reed instruments a sounding-board or box, for the purpose of rendering the tone of the instrument more musical than when constructed in the ordinary manner.

Figure 1 is a top plan view with the cover removed.

Figure 2 is a transverse vertical section, taken on the line of xx of fig. 1, with the cover closed.

Figure 3 is a section of the improvement slightly modified in its application.

A represents the case of an ordinary melodeon or similar instrument. B represents the key-board or portion occupied by the keys at the front. C represents my improvement, which consists of a box made of thin, light wood, and having one or more openings, b , in its top. This box is glued together firmly, so that there shall be no jar between its parts where united, and should be made of fine, straight-grained, sonorous wood, such as cedar or pine, though other kinds may be used, as experience shall dictate. This box thus constructed is placed upon the key-board in the top of the case, in rear of the bank of keys, as shown in fig. 2. It is secured to the board B by means of two small blocks, a , placed one under each edge at the centre, as indicated by the dotted lines in fig. 1, and as shown in section in fig. 2. If desired, it may be modified, as shown in fig. 3, in which case the box has no bottom, but instead has its lower edge glued or otherwise secured direct to the key-board B.

When the reeds are vibrated by the passage of the air, the vibration is imparted to the box C also, which operates like the shell of a violin, and greatly softens and mellows the tone of the instrument, rendering it less harsh and more flute-like.

It is obvious that this improvement may be applied to harmoniums, and all similar reed instruments, as well as to melodeons, with like results.

Having thus described my invention, what I claim, is—

In combination with the key-board of a melodeon or similar reed instrument, I claim the sounding-box C, arranged as shown and described.
